W. SWETLAND.
HOT AIR HEATER.
APPLICATION FILED NOV. 13, 1917.

1,259,314.

Patented Mar. 12, 1918.

BY
Mark Litzburg
ATTORNEY.

UNITED STATES PATENT OFFICE.

WARREN SWETLAND, OF LOS ANGELES, CALIFORNIA, ASSIGNOR TO R. H. SWETLAND,
OF CLEVELAND, OHIO.

HOT-AIR HEATER.

1,259,314.

Specification of Letters Patent. Patented Mar. 12, 1918.

Application filed November 13, 1917. Serial No. 202,058.

To all whom it may concern:

Be it known that I, WARREN SWETLAND, a citizen of the United States, residing in the city of Los Angeles, county of Los Angeles and State of California, have invented certain new and useful Improvements in Hot-Air Heaters, of which the following is a specification.

My invention relates to hot air heaters, 10 and more particularly to a heating device adapted to be supported below a floor register, for the purpose of heating and passing the hot air up into a room.

Among the salient objects of my invention are,—to provide a hot air heater adapted to be suspended or supported beneath a floor and provided with heating means whereby either the air from the room can be drawn down into the heater and returned 20 to the room after being heated, or fresh air from the outside can be directed into and through the heater and passed up into the room, as may be desired; and to provide in a device of the character referred to improved means for receiving the products of combustion, with means connected therewith for carrying off the burnt gases and odor from the products of combustion. Other objects and advantages of my improved heater will be pointed out in connection with the description of an embodiment thereof shown on the accompanying sheet of drawings, in which,—

Figure 1 is a top plan view looking down 35 into one of my improved heaters, parts being broken away for this purpose;

Fig. 2 is a horizontal sectional view thereof, taken through the middle of the heater;

Fig. 3 is a vertical sectional view through 40 the heater; and

Fig. 4 is a vertical sectional view through the heater at right angles to the view shown in Fig. 3.

Referring now more in detail to the drawings, 45 1 designates an outer casing, preferably covered with asbestos or other insulating material to conserve the heat and give protection, and is suspended or supported up under the floor, 2, beneath an opening

therein, over which is placed a register, 3, 50 which may be of any desired design.

Supported in the said outer casing 1, upon supporting bars 4, 4, therein is an intermediate casing 5, open at both ends, its upper end, however, being tapered as at 5'. Said 55 intermediate casing 5 is spaced from the outer casing by means of brackets 6, 6. Mounted within said intermediate casing, and spaced therefrom around its sides, is an inner drum 7, of box-like form, and comprising top and bottom castings, 8 and 9, provided around their edges with grooves, as at 10, 10, in which is seated the upper and lower edges of the inner drum side walls 11, as clearly shown in Fig. 3. This makes tight 60 joints and prevents the gases and odors from escaping. Mounted in said inner drum 7, are two tubes 12, 12, affording heating passageways through said inner drum, the castings 8 and 9 being provided with flanged 65 and grooved openings 13, 13, to receive the ends thereof. A heat flue 14 communicates at its upper end, through the casting 9, with the inner drum 7, and at the lower end projects through the floor of the outer casing 75 1, as clearly indicated in Fig. 3. Mounted in the casting 8, of said inner drum 7, and directly above said flue 14, is a window 15. A burner 16, here shown to be a gas burner, is mounted directly beneath the flue 14, and 80 is connected by means of suitable fittings 17, with any suitable source of gas supply. A valve 18, operated by a rod 19, extending upwardly through the floor, as at 20, provides means at the register for controlling 85 the supply of gas to said burner 16. A pilot light 21 is also provided near said burner 16, for igniting the gas when turned on. Also mounted in the bottom casting 9, is a well member 22, communicating with the 90 interior of said inner drum 7, and extending through the floor of the outer casing 1, as shown. Leading from said well casing 22 is a pipe 23, extended outwardly through the side of the casing 1, and communicating 95 with a vertical flue 24, provided at its lower end with a damper ring 25, whereby a current of air can be admitted to pass up-

wardly through said vertical flue 24, for the purpose of entraining and drawing out of the well 22, through the pipe 23, the burnt gases, odors and the like, which are caused to settle into the well 22.

Mounted in the side of the outer casing 1, is an air inlet flue 26, provided with a damper 27, operable by means of a rod 28, extended upwardly through the floor, near 10 the register, as at 29, whereby fresh air from the outside can be supplied to said outer casing at will, to pass upwardly through the intermediate casing 5, around the inner drum 7, by which it is heated, and 15 caused to pass upwardly through the register 3 and into the room. By closing the damper 27, and shutting off the inlet for the cool fresh air from the outside, the air from the room will be drawn downwardly through 20 the outer casing 1, outside the intermediate casing 5, as indicated by the outside arrows in Fig. 3, said air being drawn upwardly through the intermediate casing 5, around the inner heating drum 7, by which it is heated 25 and caused to pass upwardly into the room through the middle portion of the register, as indicated by arrows in Fig. 3. A covered manhole, at 30, is also provided in the outer casing 1, for the purpose of affording access 30 to the interior of the heater.

By providing a well 22, having the outlet flue 23, leading therefrom at a point above its bottom, and connected with the vertical flue 24, the heavier products of combustion, odors and the like, are caused to settle into said well 22, or to pass outwardly 35 through the pipe 23, and the flue 24, without allowing the heat within said inner drum 7 to escape therefrom.

40 Thus by this improved construction and arrangement, I am able to secure a maximum amount of heat in the inner drum 7, with a minimum amount of fuel, for the reason that there is no escape of the heat 45 which passes upwardly into said inner drum 7, and only the heavier and cooler products of combustion which settle are allowed to escape, and thus are drawn to the well 22, by the entraining action of the air which 50 passes upwardly through the vertical flue 24. I have also found that by shortening the intermediate casing 5, at its upper end, better results are secured than where the 55 walls of said intermediate casing are extended to the register 3.

What I claim and desire to secure patent protection for is:—

1. A hot air heater of the character shown and described comprising in combination an 60 outer casing of uniform diameter, open at its upper end and supported up under an opening through a floor, a register covering

the opening in the floor and the open upper end of said casing, an intermediate casing supported in said outer casing and spaced 65 therefrom around its sides and open at both ends, its upper end terminating in a tapered portion at a distance below said register, an inner drum mounted within said intermediate casing and spaced therefrom, said inner 70 drum being provided with a downwardly extending heat flue projecting through the floor of said outer casing, a burner mounted under the lower end thereof, a well casing 75 extending from the bottom of said inner drum to and through the bottom of said outer casing, an outlet flue connected therewith intermediate its ends and extending laterally through the side of said outer casing, an open ended vertical pipe with which 80 said outlet flue connects, whereby the passing of air upwardly through said vertical pipe creates an entraining action into said well for the heavier products of combustion within said inner drum, and one or more air 85 tubes through said inner drum vertically, substantially as shown and described.

2. A hot air heater of the character shown and described comprising in combination an outer casing of uniform diameter, open at 90 its upper end and supported up under an opening through a floor, a register covering the opening in the floor and the open upper end of said casing, an intermediate casing supported in said outer casing and spaced 95 therefrom around its sides and open at both ends, its upper end terminating in a tapered portion at a distance below said register, an inner drum mounted within said intermediate casing and spaced therefrom, said inner 100 drum being provided with a downwardly extending heat flue projecting through the floor of said outer casing, a burner mounted under the lower end thereof, a well casing extending from the bottom of said inner drum to and through the bottom of said outer casing, an outlet flue connected therewith intermediate its ends and extending laterally through the side of said outer casing, an open ended vertical pipe with which 105 said outlet flue connects, whereby the passing of air upwardly through said vertical pipe creates an entraining action into said well for the heavier products of combustion within said inner drum, one or more air 110 tubes through said inner drum vertically, and an outside air inlet pipe provided with a damper for regulating the inflow of outside air into said intermediate casing, substantially as described.

3. In a heater of the character referred to, an outer casing, an intermediate casing therein and spaced therefrom and shorter than the outer casing, an inner drum within

said intermediate casing, means for heating said inner drum, a well opening through the floor of said inner drum and extended downwardly, an outlet pipe from the side of 5 said well, and an open ended vertical pipe outside of said outer casing and with the side of which said outlet pipe connects, whereby air passing upwardly through said vertical pipe creates an entraining action in 10 said well and causes the heavier products of

combustion to settle in said well, substantially as described.

Signed at Los Angeles, Los Angeles county, California, this 8th day of November, 1917.

WARREN SWETLAND.

In presence of—

W. E. LITZENBERG,
D. P. KENDRICK.
